PIPE ORGAN

Arthur James Chase, Los Angeles, Calif.

Application February 24, 1948, Serial No. 10,252

6 Claims. (Cl. 84—1.04)

1

The present invention relates to pipe organs, and has particular reference to improvements in the design and construction of pipe organs providing an organ characterized by improved tonality.

An object of the present invention is to provide an easily transportable pipe organ of reduced overall dimension and weight, having the playing characteristics of large size, more expensive organs.

A further object of the invention is to provide an electrically operated pipe organ wherein the operational characteristics of large sized organs may be obtained with markedly reduced expenditure of money and space, in combination with a novel method for the production of tones in pipe organs.

A further object is to provide a novel pipe organ having a manual or manuals in detachable association with the tone chest.

A further object is to provide an organ pipe of novel construction and reduced scale of dimension constructed of synthetic materials such as plastics and having improved tonal qualities, the pipe being operated by low wind pressures to produce a low amplitude sound wave, and a method of forming and controlling the tone of individual plastic organ pipes.

A further object is to provide an improved electrical amplification system for use with pipe organs whereby low amplitude sound waves may be amplified without distortion of fundamentals or partials, whereby a particular desired tone color may be achieved.

Yet a further object is to provide a novel miniature pipe for use with pipe organs having tone producing qualities which upon amplification achieve full timbre and power, with the desired proper balance of partials in relation to the fundamental.

Other objects and advantages of the present invention will be apparent from the following detailed description thereof taken in connection with the drawings, wherein:

Figure 1 is a side view of the invention, showing the detachable association of the manual and the organ chest;

Figure 2 is a view taken along the line 2—2 of Figure 1;

Figure 3 is a cross-sectional view of the electrical contact means employed;

Figure 4 is a cross-sectional view of means for securing the manual to the organ chest;

Figure 5 is a perspective view of the hook means shown in Figure 4;

2

Figure 6 is a view in vertical elevation of the organ chest showing the positioning of the organ pipes and amplification system;

Figure 7 is a vertical cross-sectional view of a preferred form of organ pipe for use with the invention; and

Figure 8 is a vertical cross-sectional view of a further form of organ pipe which may be employed.

10 Referring to Figure 1 of the drawings, the numeral 10 refers to a console chest provided with a manual 11 having key banks shown as two in number, 12 and 13. The manual 11 may be of simple construction as shown, including suitable stops, single or plural pedal key banks, and other player operated tone controls of varied number and arrangement in accordance with conventional design and construction.

As shown in Figures 4 and 5, means are provided for detachably associating the manual 11 with the console chest 10, whereby the manual may be detached from the chest 10 for purposes of facilitating transportation of the organ. Said means include a plate 14 secured to the manual casing 23 by screws 15, the plate 14 being provided with a projecting hook 16 cast or otherwise formed integrally therewith. The wall 26 of the console chest 10 normally adjacent the manual casing 23 is indented at 17 and provided with a horizontal rod 18 supported by a frame 19 for engagement with the hook 16 to support the manual in playing position. Once the hook 16 is engaged with the rod 18, the manual 11 is carried under its own weight downwardly to place the casing 23 firmly adjacent the chest wall 26.

Means are provided for establishing breakable electrical connections in the circuits between the manual controls and the pipe playing mechanism in the console chest. These circuits normally are energized by manipulation of the keys and stop tablets on the manuals to effect the play on the organ, through switch controls in the console chest which are of conventional design and number, not shown. As shown in Figures 2 and 3, a breakable connection may be provided in the circuit of each key and stop tablet on the manuals or any desired combination thereof, determined by the operating characteristics of the organ. The connections include a contact plate 21 of brass or copper secured by screws 22 to the wall 23 of the manual 11 normally resting adjacent the console chest 10 when the manual is attached in playing position. A contact pin 24 may be provided to receive a wire 25, leading to a key or stop tab. The wall

26 of the console chest 10 is provided with an indentation 27 receiving a spring contact 28 secured by a suitable fastener 29 attached to a wire 30 leading to the usual switch controls in the chest for actuation of the organ pipes. Two similar contacts 28a may be provided on the opposed walls 23 and 26 respectively, connecting a source of current supply to the manual 11. Thus, it will be observed that upon assembly of the manual 11 and console chest 10, operating circuits associated with the play of the organ are established by engagement of the opposed contact members 21 and 28, which are maintained in flush position by the force exerted by the weight of the manual 11 pivoting downwardly on the hook 16.

As shown in Figure 6, the console chest 10 preferably is constructed of materials acoustically insulating the chest, such as rock wool 31 or other soft, fibrous material carried on an outer casing of wood or other desired material, forming an organ pipe enclosure 32 which inhibits reflection of sound waves from the walls with resultant formation of uneven tones detracting from a desired melodic tonality. The fibrous material 31 may advantageously be secured with an inner fibrous mat 31a, which serves to anchor the loose fibrous material 31 in place. The pipe enclosure 32 contains the usual electric motor 33 and blower 34 enclosed within a housing 35 acoustically insulated from the organ pipe enclosure 32 by fibrous material 36, which also may be secured in place by a fibrous mat 36a. Air supply ducts or trunks 37 supply air through air intakes 38, to the organ pipes 39. Air supply ducts 40 supply the blower 34, air being exhausted through an exit duct 41 in the base of the chest 10.

In accordance with the present invention, tones are produced by passing a tone producing medium such as air at a selected or predetermined pressure, through organ pipes dimensioned to produce low amplitude sound waves of desired pitch at the selected pressure and electrically amplifying the tones to normal amplitude. In practice, the wave amplitude sought is such that the tone produced is just audible to the ear, and cannot be heard outside the tone chamber of the organ. To achieve this objective, the organ pipes 39 are constructed on a scale of dimensions permitting the use of much lower wind pressures than used conventionally, for example as low as $\frac{1}{4}$ inch wind pressure, monometric water gauge. In practice, a wind pressure of $\frac{1}{2}$ inch is used, and wind pressures up to one inch are satisfactory. It has been found that by reducing the diameters of conventional pipes from one half to one fifth the width of standard organ pipe measurements, the lengths remaining standard, the low wind pressure employed produces a very low amplitude sound wave which retains complete integrity of tone upon amplification, bringing out a better balance of the partials in their relation to the fundamentals, giving a particular desired tone color.

The organ pipes of the invention may be constructed of wood, metal, paper and synthetic materials such as plastics; care being taken to form the pipes of materials having densities capable of producing desired tone timbres. For example, a pipe approximately twenty two inches long from the lower lip to the upper end, with a mouth of nine sixteenths of an inch wide and a depth from the inside upper lip to inside bottom lip of five eighths of an inch and an inside

5 mouth of approximately one quarter inch, will tune to lower C at a low amplitude, employing a wind pressure of one half inch. This pipe may be constructed on one eighth inch pipe, or paper or plastics of the same densities as pine.

10 For best results, it is preferred to construct the organ pipes of the invention of synthetic materials. It is well known that the length, diameter, density of texture, vibrating qualities, and wall thickness of materials employed in organ pipe construction are positive factors in tone and pitch production. It has been discovered that synthetic materials such as plastics and resins are particularly adaptable for this purpose. Different desired tone timbres may be obtained by employing fillers for the synthetic materials such as mineral fillers, flour, fabrics and the like, the amount of filler to be employed in a particular instance being determined by the timbre desired and the factor of pipe wall thickness. The specific plastic or resin employed depends upon the tonal properties desired in a particular organ pipe. Various combinations of different plastics and/or resins may be employed advantageously to obtain desired tone and thermal properties. It has been found, for example, that vinyl polymers such as polyvinyl chloride acetate, have much lower thermal expansion and thermal conductivity than metals, lowering variance in pitch 20 resulting from these variable factors to almost nil, in addition providing improved tone quality and performance. Commercially available synthetic materials such as methyl methacrylate resin known commercially as "Lucite," and such plastics as "Plexiglas," may be employed to advantage.

25 The plastics which are normally hard but become moldable when heated, such as vinyl polymers, cellulose derivatives and styrol resins may be preferred when it is desired to modify the structure of the pipe subsequent to initial formation in order to vary the pipe tonal character such as pitch. These synthetic materials may be classified as thermoplastic plastic compounds, contrasting with thermosetting plastics. It is to be understood, however, that any synthetic material falling within the conventional designation of "plastic," including resins and resinous type plastics, may be employed in carrying out the invention, to realize the above enumerated advantages of this new type of organ pipe.

30 As shown in Figures 7 and 8, the organ pipes 39 may be of the usual form, either round in cross section as shown, or rectangular. The pipe 39 is provided with a mouth 42, an intake vent 43, and may be open at the top at 44, as shown, or stopped. An important feature of the invention resides in the provision of means for adjusting the tone color of the individual plastic pipe 39, after fabrication of the basic pipe structure shown. This is accomplished by controlling the velocity of the air passing through the pipe 39, through the provision of partial closures or nodes along the length of the pipe, as indicated at 45. According to the preferred method of the invention, the plastic is heated to the correct temperature for softening and compressed with a simple shaping tool, not shown, deforming the structure inwardly about the pipe circumference at desired nodal points along its length. The shaped plastic section of the pipe is then cooled.

35 The partial closures 46 and 47 shown in Figure 8 may be of the same dimension or may vary in dimension in accordance with tone color requirements for a particular pipe 39. If the partial

closure 46 nearer the intake 43 is the deeper, the segment of the pipe 39 defined by the upper closure 47 will have a weaker sound wave. Inversely, if the partial closure 46 is the deeper, the sound wave is strengthened. The number of partial closures 45 employed in a particular instance may vary with the individual pipe tonal qualities desired, taking into consideration the basic requirements of pipe material density, dimension, and initial wind velocity, which are primarily determinative of pipe tonal qualities such as timbre.

Referring now to Figure 6, in view of the very low wind pressures employed in playing the organ a correspondingly low amplitude sound wave is produced by the organ pipes 39. A novel system of amplification is provided which amplifies the sound waves to achieve a desired standard volume of tone, for example, approximately two hundred times, without distortion.

The amplification equipment includes a microphone 48 suspended inside an acoustically insulated box 49, suspended upon springs 50 secured to the inside surface of the chamber 10. The microphone 48 is wired to a conventional amplifier assembly including an amplifier control unit and a loud speaker, not shown in the drawings. It is preferred that the microphone 48 be suspended in the box 49 upon springs 51 hooked into a non-metallic vibration dampening attachment 52 which may be leather or fabric. A plurality of tone trumpets 53 are secured to the sound box 49 for purposes of picking up sound waves from the ranks of pipes 39 and communicating the waves evenly to the microphone 48 through ducts 53a. The trumpets 53 are provided with dampers 54 which may be adjusted manually to control further the sound waves selected for amplification.

The microphone 48 is placed in the organ chamber so as to receive equal amplitude of sound waves from all directions, i. e., in the average center of dynamic force of sound waves produced by all pipes 39. This position may be determined in each instance in accordance with the shape of the organ chamber 10 and the organ pipes' specifications and placement. Final adjustments of wave amplitude to a degree permitting of markedly accurate tone modulation and blending, may be accomplished by manipulation of the dampers 54 of the trumpets 53.

It will be observed that the present invention provides a novel pipe organ operating on a new principle of sound control and reproduction, whereby the overall dimension of the organ may be reduced considerably from that of conventional organs without sacrificing any desirable operational characteristics of the larger organs. The reduction in wind pressures employed permits of using simplified, less expensive equipment, and the organ pipe of the invention produces a very low amplitude sound wave which may be amplified without distortion of fundamentals or partials, giving the particular color tone desired.

The pipes employed may be constructed of wood, metal, or paper. However, best results are obtained by employing plastics having material densities adjusted in accordance with the vibrational characteristics desired in the pipe, the pipe being further modified by nodular deformation to achieve an exact desired characteristic tonal quality.

The provision of a detachable manual permits of movement of the organ in the door of any resi-

dence or building without structural modification of the door or chambers of the residence.

The amplification system permits of fine adjustment of tonal qualities, producing a tone rich and full in timbre and power. The new method of tone production brings out a better balance of the partials in their relations to the fundamental than has been accomplished heretofore through amplification of tones initially very low in amplitude, with proper positioning and adjustment of the amplification equipment relative to the tone sources.

The invention has been set forth herein with reference to the specific structures described and shown in the drawings, for purposes of description only, and is not to be regarded as limited thereby, except as defined in the appended claims.

I claim:

20. 1. The method of producing tones in a pipe organ comprising passing a tone producing medium under predetermined pressure through organ pipes dimensioned to produce low amplitude sound waves of desired pitch at the predetermined pressure, and amplifying the low amplitude sound waves to produce tones of normal amplitude characterized by balanced tonal relationship and integrity of tone color.
25. 2. The method of producing tones in a pipe organ comprising passing air at reduced pressure through organ pipes dimensioned to produce low amplitude sound waves at the selected low pressure providing an audible tone of desired pitch and sub-normal amplitude, and electrically amplifying the low amplitude sound waves to produce tones of normal amplitude at the desired pitch characterized by balanced tonal relationship and integrity of tone color.
30. 3. The method of producing tones in a pipe organ comprising passing air at a pressure between one quarter and one half inch wind pressure, monometric water gauge, through pipes reduced in cross-sectional dimension to produce low amplitude sound waves of a desired pitch at the selected pressure, and electrically amplifying the low amplitude sound waves to produce tones of normal amplitudes characterized by integrity of tonal relationship and tone color.
35. 4. The method of producing tones in a pipe organ comprising passing air at a pressure between one quarter and one half inch wind pressure, monometric water gauge, through pipes dimensioned to produce low amplitude sound waves of a desired pitch at the selected wind pressure, controlling the velocity of air passing through selected pipes to modify the characteristic low amplitude sound waves normally produced by the pipes, and electrically amplifying the sound waves of characteristic and corrected low amplitude to produce tones of normal amplitudes characterized by integrity of tonal relationship and tone color.
40. 5. The method of producing tones in a pipe organ comprising passing air at a pressure between one quarter inch and one inch wind pressure, monometric water gauge, through organ pipes to produce low amplitude sound waves of a desired pitch at the selected pressure in a tone chamber, dampening out selected low amplitude sound waves in the tone chamber, and electrically amplifying the screened low amplitude sound waves in the tone chamber to produce tones of normal amplitudes characterized by integrity of tonal relationship and tone color.
45. 6. The method of producing tones in a pipe
50. 7. The method of producing tones in a pipe organ comprising passing air at a pressure between one quarter and one half inch wind pressure, monometric water gauge, through pipes dimensioned to produce low amplitude sound waves of a desired pitch at the selected pressure, controlling the velocity of air passing through selected pipes to modify the characteristic low amplitude sound waves normally produced by the pipes, and electrically amplifying the sound waves of characteristic and corrected low amplitude to produce tones of normal amplitudes characterized by integrity of tonal relationship and tone color.
55. 8. The method of producing tones in a pipe organ comprising passing air at a pressure between one quarter and one half inch wind pressure, monometric water gauge, through pipes dimensioned to produce low amplitude sound waves of a desired pitch at the selected pressure, controlling the velocity of air passing through selected pipes to modify the characteristic low amplitude sound waves normally produced by the pipes, and electrically amplifying the sound waves of characteristic and corrected low amplitude to produce tones of normal amplitudes characterized by integrity of tonal relationship and tone color.
60. 9. The method of producing tones in a pipe organ comprising passing air at a pressure between one quarter and one half inch wind pressure, monometric water gauge, through pipes dimensioned to produce low amplitude sound waves of a desired pitch at the selected pressure, controlling the velocity of air passing through selected pipes to modify the characteristic low amplitude sound waves normally produced by the pipes, and electrically amplifying the sound waves of characteristic and corrected low amplitude to produce tones of normal amplitudes characterized by integrity of tonal relationship and tone color.
65. 10. The method of producing tones in a pipe organ comprising passing air at a pressure between one quarter and one half inch wind pressure, monometric water gauge, through pipes dimensioned to produce low amplitude sound waves of a desired pitch at the selected pressure, controlling the velocity of air passing through selected pipes to modify the characteristic low amplitude sound waves normally produced by the pipes, and electrically amplifying the sound waves of characteristic and corrected low amplitude to produce tones of normal amplitudes characterized by integrity of tonal relationship and tone color.
70. 11. The method of producing tones in a pipe organ comprising passing air at a pressure between one quarter and one half inch wind pressure, monometric water gauge, through pipes dimensioned to produce low amplitude sound waves of a desired pitch at the selected pressure, controlling the velocity of air passing through selected pipes to modify the characteristic low amplitude sound waves normally produced by the pipes, and electrically amplifying the sound waves of characteristic and corrected low amplitude to produce tones of normal amplitudes characterized by integrity of tonal relationship and tone color.
75. 12. The method of producing tones in a pipe

organ comprising passing air at a pressure between one quarter inch and one inch wind pressure, monometric water gauge, through organ pipes dimensioned to produce low amplitude sound waves of a desired pitch at the selected pressure in a tone chamber, the sound waves being of an amplitude approaching inaudibility, shaping selected pipes to control the velocity of wind passage through said pipes to modify further the characteristic low amplitude of the sound waves normally produced by the selected pipes, dampening out selected low amplitude sound waves in the tone chamber, and electrically amplifying the screened low amplitude sound waves in the tone chamber to produce tones of normal amplitudes characterized by integrity of tonal relationship and tone color.
